UNITED STATES PATENT OFFICE.

WALTER O. AMSLER, OF PITTSBURGH, PENNSYLVANIA.

GAS BURNER.

Application filed August 7, 1922. Serial No. 580,074.

To all whom it may concern:

Be it known that I, WALTER O. AMSLER, a citizen of the United States, residing at Pittsburgh, in the county of Allegheny and 5 State of Pennsylvania, have invented certain new and useful Improvements in Gas Burners, of which the following is a specification.

This invention is for an improvement in 10 gas burners for furnaces, particularly glass furnaces or open hearth furnaces, or furnaces of a similar kind.

In furnaces of this kind, it is necessary 15 to pass a flame over a considerable area of the interior of the furnace. The more even the distribution of the flame over the entire area to be covered, the more efficient is the operation of the furnace. As most of these furnaces are of a regenerative or recuperative type, the interior of the burner is subject to very high temperatures.

It has heretofore been the general practice in furnaces of this kind to provide a series of burner ports along each side of 25 the furnace placed as close together as possible. A separate burner construction behind each port included a mixing passage, having at its rear a substantially horizontal partition separating the gas and the air 30 passages. Due to the intense heat to which the interior of the burner is subject, this partition as commercially used can have only a very limited width, and if its width were increased, it could not sustain its 35 weight under the prevailing high temperature conditions. Consequently, the burner ports can have only a very limited width. As the burners are necessarily made of refractory walls of appreciable thickness, 40 these ports, of necessity, are spaced some distance apart. Thus, the area of the furnace to be heated is traversed by a relatively large number of strips of flame between which are strata of air.

45 The present invention has for its principal object to provide a substantially horizontal partition of simple construction inside the burner, which may be of a much greater width, so that the burner ports may 50 have a greatly increased width. The number of burners may thus be reduced, and a larger area of the furnace traversed by the flame, many of the intervening spaces being eliminated.

55 The invention may be readily understood

by reference to the accompanying drawings, in which:

Fig. 1 shows a longitudinal section through a burner embodying my invention, the burner being shown in connection with a glass furnace;

Fig. 2 is a transverse section in the plane of line II—II of Fig. 1;

Fig. 3 is a similar section in the plane of line III—III of Fig. 1;

Fig. 4 is a view similar to Fig. 1, showing parts of the burner broken away, of a modified construction; and

Fig. 5 is a partial section in the plane of line V—V of Fig. 4.

In the drawings, 5 indicates a furnace, such for instance, as a glass furnace having a top 6, side walls 7, tuckstone 8, and pot 9. In the side walls 7, are the burner ports 10 which are relatively wide and slightly arched.

Resting on the tuckstone and extending outwardly is a flat bottom wall 11, forming the bottom of the burner. The outer end of this wall rests on a vertical wall 12. An inclined arched wall 13 forms the top of the burner, this wall extending rearwardly to vertical wall 14 and resting on side walls 15.

Built against the vertical wall 12 is refractory wall 16 that increases rearwardly in width toward the top thereof. Separating the space between walls 14 and 16 is an intermediate vertical wall 17. A vertical air passage 18 is thus formed between walls 14 and 17, and a vertical gas passage 19 is formed between walls 16 and 17. The horizontally extending mixer passage is designated as 20.

In order to provide horizontal passages opening into the mixer 20, a horizontally extending wall must be placed above wall 17 to deflect the gas ascending passage 20 toward the burner port. Heretofore, difficulty has been encountered in making the wall sufficiently wide and yet be self-sustaining.

The present invention proposes to set a refractory block or blocks on the top of the wall 17 in such manner that their center of gravity will be over the vertical wall, while such block will have a forwardly extending portion projecting beyond wall 17 sufficiently far to make the desired partition.

In Figs. 1 and 2, I have shown the burner

having a series of blocks therein of a preferred form, utilizing a cantilever principle. These blocks, designated 22, have a relatively wide heavy base portion 22^a and are set 5 side by side on the top of wall 17. The upper parts of the blocks have forwardly extending lip portions 22^b which overhang the top of wall 16, thus providing a horizontal gas passage 23. The block may have a 10 beveled face at 22^c. The lip portions of the blocks may have registering openings 22^d therein, through which cooling air or other cooling medium might be passed.

The blocks are so designed that the base 15 portion overbalances the lip and the center of gravity of the block is over the wall, so that each block keeps itself in position. Consequently, no part of the partition formed by the blocks is under any considerable strain, and the partition could be made 20 of any desired width. Furthermore, a partition so formed does not need any special supporting means in the side walls of the burner, so that it can be easily and cheaply 25 installed. The blocks, being relatively small, can be readily renewed, or replaced.

In Figs. 4 and 5, the same reference characters have been used to designate parts corresponding to the parts shown in Fig. 1, 30 the constructions being identical. In this construction, however, the wall 17 is extended higher upwardly, and its top is inclined. The horizontal partition is formed by two blocks 25, resting on the top of wall 35 17. The blocks are placed end to end, and the outer end of each block is embedded in a side wall 15 to prevent them from sliding forwardly. These blocks overhang wall 16 a sufficient distance, but their center of 40 gravity is such that they have no tendency to tilt forward.

Various changes and modifications may be made within the contemplation of my invention, and within the scope of the appended 45 claims.

What I claim is:

1. A burner construction for furnaces comprising an air passage, a vertical gas passage, a vertical wall within the burner, and 50 means resting on said wall and projecting in lateral direction beyond said wall across the top of the gas passage to form a partition between the air and gas passages inside the burner structure at the point of juncture of said passages, said means having its center of gravity disposed over the vertical wall whereby it is held.

2. A burner construction for furnaces comprising a vertical air passage, a vertical 60 gas passage, a wall between the passages, a horizontally extending mixer passage into which air and gas passages lead, and a block on the wall having a portion thereof projecting beyond the wall entirely across the 65 gas passage but spaced above the gas passage

to form a partition between the air and gas passages at the point of juncture of the two passages, said block having its center of gravity disposed to the rear of the projecting portion so that it maintains its proper position on said wall. 70

3. A burner construction for furnaces comprising an air passage and a gas passage which are separated by a wall, and a mixer passage into which the air and gas 75 passages merge, and means for separating said passages at the point of juncture to obtain a flame of the desired area comprising a plurality of blocks resting on and entirely supported by said wall, said blocks having portions thereof extending laterally and downwardly beyond the wall over the gas passage and forming a partition between the air and gas passages and serving to direct the gas flow from said passage laterally and downwardly into the mixer passage. 80

4. A burner construction for furnaces comprising a vertical air passage and a vertical gas passage divided by a vertical wall; a horizontally extending burner passage into which said vertical passages lead, and a plurality of substantially contiguous blocks resting on and supported by said vertical wall, said blocks having horizontally projecting portions overhanging said wall and extending entirely across the top of the gas passage into said horizontally extending passage and forming a horizontally extending partition thereacross. 90

5. A burner construction for furnaces comprising a vertical air passage and a vertical gas passage, a vertical wall between said passages, a horizontally extending burner passage into which said air and gas passages lead, and means for providing a horizontally extending partition in the rearmost portion of the burner passage for directing the flow of gases in the passages comprising a series of substantially contiguous blocks set on the top of said vertical wall, and supported thereby, said blocks having heavy base portions and forwardly extending lip portions overhanging the wall and projecting entirely over the gas passage into the burner passage, the center of gravity of the blocks being in the base portion thereof. 100

6. A burner construction for furnaces comprising a vertical air passage and a vertical gas passage, a vertical wall between said passages, a horizontally extending burner passage into which said air and gas passages lead, and means for providing a horizontally extending partition in the rearmost portion of the burner passage for directing the flow of gases in the passages comprising a series of substantially contiguous blocks set on the top of said vertical wall, and supported thereby, said blocks having heavy base portions and forwardly extending 115 120 125 130

ing lip portions overhanging the wall and projecting entirely over the top of the gas passage into the burner passage, the center of gravity of the blocks being in the base portion thereof, the lip portions of the blocks having registering openings therein for passage of a cooling medium therethrough.

7. In melting tank construction, the combination of a hearth, a burner port leading into said hearth and downwardly inclined in relation thereto, a gas-uptake and an air-uptake connected at their upper ends with said port, a division wall separating said uptakes, and a tongue-block mounted on said wall and extending over the top of the gas-uptake and into said port above the mouth of the gas-uptake.

8. In melting tank construction, the combination of a hearth, a burner port leading into said hearth, an air-uptake and a gas-uptake connected at their upper ends with said port, a division wall separating said uptakes, and a plurality of canti-lever tongue-blocks mounted in a row on top of said division wall and provided with integral tongue portions of sufficient length to extend over the top of the gas-uptake and into said port, the surfaces of said tongue portions being inclined to restrict the gas-opening and direct the gas downwardly toward the hearth of the tank.

In testimony whereof I affix my signature.

WALTER O. AMSLER.
